(Cl. D44—15)

To all whom it may concern:

Be it known that I, Clara Brock, a citizen of the United States of America, residing in the city of Los Angeles and county of Los Angeles and State of California, have invented a new, original, and ornamental Design for a Dinner Plate or Similar Article, of which the following is a specification, reference being had to the accompanying drawing, forming a part thereof.

The single figure of the drawing is a top plan view of a dinner plate having a conventional configuration, embodying my new design.

I claim:

The ornamental design for a dinner plate or similar article, substantially as shown and described.
